(57) **CLAIM**

The ornamental design for an emergency cardiac and electrocardiogram electrode placement system, as shown and described.

DESCRIPTION

FIG. 1 is a top plan view of an emergency cardiac and electrocardiogram electrode placement system, showing our new design;

FIG. 2 is a bottom plan view thereof;

FIG. 3 is a front elevation view thereof;

FIG. 4 is an enlarged isolated view of the ellipse 4 of FIG. 3;

FIG. 5 is an enlarged isolated view of the ellipse 5 of FIG. 3;

FIG. 6 is a rear elevation view thereof;

FIG. 7 is an enlarged isolated view of the ellipse 7 of FIG. 6;

FIG. 8 is an enlarged isolated view of the ellipse 8 FIG. 6;

FIG. 9 is a side elevation view thereof;

FIG. 10 is an enlarged isolated view of the ellipse 10 of FIG. 9;

FIG. 11 is an enlarged isolated view of the ellipse 11 of FIG. 9;

FIG. 12 is a side elevation view thereof;

FIG. 13 is an enlarged isolated view of the ellipse 13 of FIG. 12; and,

FIG. 14 is an enlarged isolated view of the ellipse 14 of FIG. 12.

The broken lines in the drawings depict environmental structures and form no part of the claimed design.
